UNITED STATES PATENT OFFICE.

THEODORE LINKE, OF NEW YORK, N. Y.

DESIGN FOR A FILTER-BODY.

SPECIFICATION forming part of Design No. 33,173, dated September 4, 1900.

Application filed September 12, 1899. Serial No. 730,275. Term of patent 7 years.

To all whom it may concern:

Be it known that I, THEODORE LINKE, a citizen of the United States, residing at New York, in the county of New York and State 5 of New York, have invented and produced a new and original Design for a Filter-Body, of which the following is a specification, reference being had to the accompanying drawings, forming part thereof, and in which—

Figure 1 is a side view of a filter-body bearing and incorporating my design, and Fig. 2 is a top view of same.

The leading feature of my design consists of the exterior form and configuration of the 5 filter-body, substantially as shown in the drawings.

In the drawings, A designates the main body, said body being cylindrical in outline and having at its upper end the ornate cap,

comprising the annual convex section B and 20 downwardly and outwardly concaved portion C, which terminates at the convex section B and has the polygonally-formed part D. Below the body A are the portions E, F, G, H, and I, of the contour illustrated, the whole 25 comprising a filter-body of ornate form and configuration.

What I claim is—

The design for a filter-body, substantially as shown and described.

Signed at New York, in the county and State of New York, this 11th day of September, A. D. 1899.

THEODORE LINKE.
